CLAIM

The ornamental design for a pacifier clip, as shown and described.

DESCRIPTION

FIG. 1 is a top, front, right perspective view of a pacifier clip, shown closed in a first configuration;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a top, front, right perspective view of the pacifier clip of FIG. 1, shown open in a second configuration for clarity of disclosure.

The broken lines in the drawings depict portions of the pacifier clip that form no part of the claimed design.

1 Claim, 6 Drawing Sheets
